UNITED STATES PATENT OFFICE.

FRANK E. HALL, OF BOSTON, MASSACHUSETTS.

IMPROVEMENT IN RUBBER OVERSHOES.

Specification forming part of Letters Patent No. 151,970, dated June 16, 1874; application filed
March 4, 1874.

To all whom it may concern:

Be it known that I, FRANK ELMER HALL, of Boston, in the county of Suffolk, State of Massachusetts, have invented a certain new and useful Improvement in Rubber and Water-Proof Overshoes, of which the following is a description sufficiently full, clear, and exact to enable any person skilled in the art or science to which my invention appertains to make and use the same, reference being had to the accompanying drawing forming a part of this specification, in which—

Figure 1 is an isometrical perspective view of my improved protector. Fig. 2 is a vertical longitudinal section of a shoe provided with the protector.

Like letters refer to like parts in the different figures of the drawing.

My invention relates to rubber shoes designed for overwear; and consists in a shoe provided with a metallic protector, disposed in the heel of the same, as hereinafter more fully set forth and claimed, the object being to preserve the shape of the shoe, and increase its durability at that point.

The extreme simplicity of my invention renders an elaborate description unnecessary.

The protector is made of metal, and formed as shown in Fig. 1, having an upright flange, A, and horizontal flange a, and may be cast or struck from thin sheet metal, as preferred. The flange A is flaring, or stands at an acute angle with the flange a. In Fig. 2, C is the

body of the shoe, C' the heel, and B B the lining.

The protector A is introduced when the shoe is molded and before vulcanization, being placed at the junction of the upper C and sole or heel C', and between the outer and inner portions of the shoe, as shown, and the shoe is then completed by vulcanization.

It is well known that ordinary rubber overshoes are rapidly cut out and destroyed by the nails in the heels of the inner boot or shoe; also, that they are liable to run over or "bag" at the heel, and wear unevenly. These difficulties are entirely obviated by the protector, which not only keeps the quarters of the overshoe expanded and in place, but also prevents the nails of the inner shoe from cutting through the heel or sole of the rubber.

The protector is valuable in all water-proof overshoes constructed of rubber; but is especially valuable in the lighter forms of rubber overshoes for the reasons stated.

Having thus described my invention, what I claim is—

In a rubber shoe, a metallic heel re-enforce, having an inwardly-projecting flange to sustain and protect the tread of the heel, and vulcanized between the inner and outer portions of the heel, as specified.

FRANK E. HALL.
